UNITED STATES PATENT OFFICE

147,499

DESIGN FOR A WATERPROOF FOOT COVERING

Thomas F. Gibbs and Frank E. Conner, Jr., Lakewood, and William E. Donahue, Euclid, Ohio

Application December 23, 1946, Serial No. 135,714

Term of patent 14 years

(Cl. D47—7)

To all whom it may concern:

Be it known that we, Thomas F. Gibbs, a citizen of the United States of America and a resident of Lakewood, in the county of Cuyahoga and State of Ohio; William E. Donahue, a citizen of the United States of America, and a resident of Euclid, in the county of Cuyahoga, and State of Ohio, and Frank E. Conner, Jr., a citizen of the United States of America, and a resident of Lakewood, in the county of Cuyahoga, and State of Ohio, have invented a new, original, and ornamental Design for a Waterproof Foot Covering, of which the following is a specification, reference being had to the accompanying drawing, forming a part thereof, in which:

Fig. 2 is a front elevational view of the waterproof foot covering.

We claim:

The ornamental design for a waterproof foot covering, as shown.

THOMAS F. GIBBS,
FRANK E. CONNER, JR.
WILLIAM E. DONAHUE.
